Attorneys.

UNITED STATES PATENT OFFICE.

JOSEPH SCHMIDT, OF MILWAUKEE, WISCONSIN.

RIM TOOL.

Application filed February 18, 1920. Serial No. 358,934.

To all whom it may concern:

Be it known that I, JOSEPH SCHMIDT, a citizen of the United States, and resident of Milwaukee, in the county of Milwaukee, 5 and State of Wisconsin, have invented certain new and useful Improvements in Rim Tools; and I do hereby declare that the following is a full, clear, and exact description thereof.

10 My invention has for its object to provide a simple, economical and effective tool for breaking the joint in demountable rims for the purpose of removing or replacing tires.

15 Another object of my invention is to provide a combination tool for the purpose specified wherein certain of the parts are sold in sets whereby a series of rims may be operated upon with an actuating mechanism 20 which is removable from one set of the devices to the other, thus a plurality of rims may be manipulated and locked up with a single actuating device.

With the above objects in view the invention consists in certain peculiarities of construction and combination of the parts as hereinafter set forth with reference to the accompanying drawings and subsequently claimed.

30 In the drawings:

Figure 1 represents a side elevation of a portion of a clincher rim having attached thereto a tool embodying the features of my invention, the parts of the tool being shown in position to break the rim.

Figure 2 is a plane view of the same with parts broken away and in section to show certain structural features.

Figure 3 is a side elevation of the rim locking elements of the tool showing the same in position upon a rim which is contracted and locked, the actuating lever of the tool being removed.

Figure 4 is a detail cross section of one 45 of the rim gripping elements embodying a portion of the tool this section being indicated by the line 4-4 of Figure 3, and

Figure 5 is a detail fragmentary view of the lower portion of the actuating lever of 50 said tool.

Referring by characters to the drawings A-A' represent the ends of a split rim of any known type and at a predetermined

distance from the joint between the rim sections. A pair of grips 1-1' are fitted to the rim. As best shown in Figure 4 each of these grips comprise separable straps having hooked ends 2 which fit over the rim bead and at an intermediate point the grips are formed with inwardly extended flanges 3 which rest upon the inner face of the rim. An upstanding ear portion 4 of the grip is apertured for the reception of a tie bolt 5, which tie bolt is in threaded union with a hand nut 6 whereby the separable portions 65 of the rim grip are adjustably fitted to the rim and held frictionally to prevent slippage. The grip member 1 as shown in Figure 4 has loosely mounted upon the bolt 5 a locking dog 7 which dog terminates with 70 the hooked end 7' that is adapted to be folded over for engagement with the tie bolt 5' of the rim grip 1'. When the rim sections A-A' have been contracted by manipulation of the two in which position they are shown 75 in Figure 3 of the drawings being locked by the dog 7.

The tie bolt 5' has mounted thereon a spacing sleeve 8 which is stopped at one end a predetermined distance from the ear 4 to 80 form clearance space for the reception of the lower end of an actuating link 9, which lower end is apertured for the reception of the bolt that constitutes a pivot connection therefor.

The upper end of the actuating link 9 is provided with a series of perforations 9' for locking engagement with a key pin 10 that is fitted through any one of a series of apertures 10' formed in the lower end of an 90 actuating lever 11. The extreme end of the actuating lever 11, as best shown in Figure 5 is provided with a T-shaped slot 12 adapted for removable engagement with the tie bolt 5 of the grip 1 there being a space between the shank of the locking dog and the juxtaposed ear 4 of the grip member for the reception of the slotted end of this lever. The T shape of the lever serves to make the lever reversible. The lever is 100 adapted to be entirely removed from its cooperate parts excepting the chain and pin, and may be used in connection with other similar parts with arm of the T shaped slot, therefore adapted to engage with a bolt. 105 Thus it is unnecessary that the lever should

be operated in one particular direction, it is reversible and the bolt may be engaged in either arm of the T shaped slot.

As best shown in Figure 2 of the drawings 5 the lever is preferably constructed from a malleable strip folded upon itself so as to provide the necessary strength and the folded lower ends are each formed with a key hole slot as shown in Figure 5. The folded 10 sections of the lever 11 are secured together at an offset portion by a rivet 13, which rivet is formed with an eye head 13' that is provided for the reception of one end of a chain to the lower end of which is attached the 15 locking pin 10 as shown in Figure 1.

From the foregoing description it will be seen that when the parts are in the position shown in Figure 1 should it be desired to break and contract the rim member the actuating lever may be first swung in the opposite direction from that indicated by the arrow α . The joint of the rim, due to the pressure being put upon the lever and link in this direction will open or spread the 25 rim sections causing them to break out of alignment. The actuating lever is then swung in the direction indicated by the arrow α whereby the ends of the rim are contracted and folded upon themselves as 30 shown in Figure 3 of the drawings. Thus the tie bolts of the rim grips are brought together approximately a distance equal to the length of the locking dog. The locking dog is swung by hand to cause the nose of 35 the locking dog to nest over the bolt 5' and its associated thimble 8 whereby, the gripping members are securely fastened in their contracted relation so as to hold the rim in the position shown in Figure 3.

40 Should it be desired to manipulate one or a series of rims in a like manner the operator will then simply remove the pin 10 to free the link 9 from the actuating lever 11 and thereafter said lever can be readily extracted 45 from its fulcrum engagement with the tie bolt 5 due to the key hole slot at its end. The lever is then utilized for coupling engagement with a similar set of rim grips and their associated parts, the locking dog 50 7 and link 9. This interchangeability of actuating mechanism is an important feature in repair shops where a number of rims are to be worked upon and thus a great saving in cost of rim tools is effected where 55 more than one tool can be economically put into use. Obviously in cases where a single tool only is used the removed feature of the lever 11 may be dispensed with.

Attention is directed to the fact that I 60 provide a series of apertures in the link and lever whereby they may be pivotally connected by the locking pin 10 at predetermined distances from their fulcrummed points whereby the leverage or toggle link connection is varied to provide for manipulating

rims wherein a greater or less degree of power is required. Thus when a stiff rim is to be manipulated the leverage between the link and actuating lever is shortened so as to increase power and vice versa.

70 While I have shown and described the structure of the tool minutely as to detail it is understood that changes in such detail structure may be effected without departing from the spirit of my invention.

I claim:

1. In a device of the class described, the combination of a lever made of a single elongated piece of metal, bent at the middle and extending in substantially parallel 80 stretches, forming a handle portion throughout which the stretches are in close contact and an actuating portion having a T shaped slot in the end thereof for cooperation with a bolt, the arms of the T receiving the bolt 85 and retaining the lever in engagement therewith, the lever being reversible in its usage with the bolt, whereby either arm of the T may receive the bolt, the lever having a series of spaced apertures in its actuating 90 part and being deflected laterally between said actuating part and said handle, and a rivet extending thru the laterally deflected portion for securing the stretches of metal rigidly together, an eye rigid with 95 said rivet, a chain carried by said eye and a pin carried by said chain, the lever being deflected laterally to facilitate movement of the lever without causing the lever to come in contact with the hub of the wheel.

100 2. In a rim tool, a pair of oppositely disposed jaws, a pair of inwardly directed hooks on said jaws for gripping the exterior surface of the rim, a projection on said jaws having relatively large superficial contact with the inner face of the rim, a pair of apertured lugs on said jaws extending inwardly in a radial direction from the rim, substantially at right angles to said projection, a bolt in the apertures of a pair of said lugs, a sleeve on said bolt, a flat link having an aperture receiving said bolt, said link abutting against one of said lugs and said sleeve, said link having a series of openings 110 at its free end, a second bolt in the apertures of the other pair of said lugs, a long, relatively wide dog having one end formed into a sleeve embracing said second bolt, said dog being formed into a wide hook at its other end for embracing said first mentioned sleeve, the width of the hook preventing deformation of said first mentioned bolt, an actuating lever having a T-shaped slot therein for movably engaging with said second bolt between said dog and one of said lugs 125 and having a series of apertures to be selectively aligned with the apertures of the permanent link member and a removable pin for hingedly connecting the link and lever together, whereby variations in leverage be- 130

tween said link and lever are effected, the removable lever being adapted for use in connection with a series of contracting and locking elements that are attached to other arms, said lever being split and receiving said permanent link member between its split portions and nuts on said bolts for

causing said lugs to approach and thus exerting a tightening action.

In testimony that I claim the foregoing I 10 have hereunto set my hand at Milwaukee, in the county of Milwaukee and State of Wisconsin.

JOSEPH SCHMIDT.
